RECORD PLAYER OR SIMILAR ARTICLE

Jon W. Hauser, St. Charles, Ill., assignor to Hawley Products Company, St. Charles, Ill., a corporation of Delaware

Application March 7, 1955, Serial No. 34,880

Term of patent 14 years

(Cl. D56—4)

FIG. 1

FIG. 2

FIG. 4

Fig. 1 is a top plan view of a record player or similar article, embodying my new design;

Fig. 2 is a front elevational view thereof;

Fig. 3 is a back elevational view thereof; and

Fig. 4 is a side elevational view thereof.

The dominant features of my design reside in the portions shown in full lines.

I claim:

The ornamental design for a record player or similar article, as shown and described.
